SINTERING FURNACE

George C. Burgess, Columbia, Tenn.

Application October 9, 1947, Serial No. 778,879

2 Claims. (Cl. 266—21)

1

This invention relates to a sintering furnace and has for its object the provision of a furnace of the character designated which shall be adapted to operate continuously, receiving a sintering charge of mixed fuel and material to be sintered, such as ore, and discharge the sintered material therefrom, which furnace shall be of large capacity, reliable in operation, and one which will not become overheated in operation.

A further object of my invention is to provide a continuously operating sintering furnace which shall include improved means to control the ignition and burning of the fuel in the sintering charge.

A still further object of my invention is to provide a continuously operating sintering furnace which shall embody a rotary drum having a gas permeable surface, with a stationary suction chamber disposed within the drum and with improved means to seal off the suction chamber from the greater portion of the drum and thus confine the feeding and sintering of the charge to a limited area of the drum.

Another object of my invention is to provide a continuous sintering furnace embodying a rotary drum with means to feed a sintering charge of ore and fuel onto the surface of the drum, means to control the rate of feed to maintain an even thickness of charge, and means to control the rate of combustion of the fuel in the charge thereby to prevent overheating of the furnace.

Apparatus embodying features of my invention is illustrated in the accompanying drawings forming a part of this application, in which:

Fig. 1 is an end elevational view;

Fig. 2 is a plan view with parts broken away;

Fig. 3 is a sectional view taken generally along the line III—III of Fig. 1;

Fig. 4 is a sectional view, partly diagrammatic, taken generally along the line IV—IV of Fig. 3; and

Fig. 5 is a diagrammatic sectional view showing the means for controlling the rate of combustion on the drum.

Referring to the drawings for a better understanding of my invention, my improved apparatus embodies a foundation, or base plate, 10 having end supporting cradles 11 and 12 erected thereon, each having a semicircular seat 13 therein, as shown in Fig. 1. Supported by the cradles in a manner to be described later is my improved furnace which embodies a rotary drum indicated generally by the numeral 14. The drum is made up of end rings 16 and 17 joined together by a plurality of longitudinally extending bars 18.

Supported by the bars 18 are a series of grates 19 which form a gas permeable surface for the drum to support the sintering charge of mixed fuel and ore thereon. Mounted on the end rings 16 and 17 are a series of extension rings 21 and 22 which extend entirely around the drum, as shown in Fig. 3, to provide lateral support for the sintering charge. The end rings 16 and 17 are provided with inwardly directed flanges 23 and 24 having grooves 26 and 27 therein in which are mounted sealing rings 28 and 29. Each of the rings 28 and 29 comprises outer rings 28a and 29a formed preferably of graphite, and inner rings 28b and 29b formed of steel or cast iron. Extending longitudinally of the drum, and joining the inwardly directed flanges 23 and 24 are a series of sealing strips 31.

Mounted on the ends of the drum and secured to the rings 16 and 17 are a plurality of brackets 32 and 33 for supporting riding rings 34 and 36, which latter are secured to the brackets. Mounted in the seats 13 of the cradles 11 and 12 are roller bearings 37 and 38 on which the riding rings 34 and 36 bear. The rollers of the bearings are retained by spacing rings 39 and 41 at each end of the drum. Also secured to the brackets 32 and 33 inwardly of the riding rings 34 and 36, are ring gears 42 and 43 each having its gear teeth on the inner surface thereof. At 44 I show a driving motor which drives a shaft 46 by means of suitable sprockets and a sprocket chain 47. The shaft 46 extends entirely through the drum 14 and has mounted thereon pinions 48 and 49 which mesh with the ring gears 42 and 43 to drive the drum.

Mounted within the drum 14 is a stationary suction chamber comprised of end walls 51 and 52 and side walls 53 and 54. The side walls 53 and 54, as shown in Fig. 5 of the drawing, extend below the center of the drum 14 to form a trough 56. The trough 56 terminates in flanged openings 57 and 58, extending through the end walls 51 and 52, to which are connected suction conduits 59 and 61. Mounted within the trough 56 is a screw conveyor having ribbon flights 62 and 63 mounted on a shaft 64. As shown in Fig. 3, the flights 62 and 63 are turned in opposite directions so that any solid matter passing through the grates 19 will be delivered out at the ends through the suction openings 59 and 61. The shaft 64 is driven from the shaft 46 as shown in Fig. 2 of the drawing as by means of the belt 66 and pulleys 67 and 68.

As shown in Fig. 3, the end walls 51 and 52 are provided with inwardly turned flanges 69 and 71 which are concentric with the inwardly directed

flanges 23 and 24 of the end rings 16 and 17 and cooperate with the sealing rings 28 and 29 to prevent the flow of air into the suction chamber through the ends of the drum. Also, as shown in Fig. 4 of the drawing, the side walls 53 and 54 of the suction chamber are provided at the top with skirts 72 and 73 which are concentric with the drum and which are of such length as to span the arc between a pair of sealing strips 31. Thus, one sealing strip always is cooperating with each of the skirts 72 and 73 to intercept the flow of air into the suction chamber around the side walls thereof.

At the ends of the suction conduits 59 and 61, respectively, are disposed cyclone separators 74 and 76 for separating from the gases of combustion any dust or solid material passing through the grate 19 into the suction chamber. Each of the cyclone separators is provided with a hinged weighted trap door 77, as shown in Fig. 1, to discharge solid material therefrom when sufficient accumulates to open the trap door.

Connected to the cyclones 74 and 76 are suction conduits 78 and 79 which are in turn connected at their other ends to a single conduit 81 leading to a motor driven exhaust blower 82. The suction chamber, suction conduits, and cyclone separators, are supported by means of end supports 83 and 84 extending downwardly to the base or foundation plate 10.

The sintering charge, which, as is well understood, consists of a mixture of fuel and material to be sintered, is fed on the drum through a feed chute 86, the rate of feed being controlled as by a motor driven rotary feeder 87. As the charge falls on the drum, it is leveled off by means of a leveling bar 88 extending across the chute 86 immediately above the drum. The charge is ignited by means of downwardly directed gas jets 89 and combustion is maintained by the air being drawn through the charge and the grate 19 by the blower 82.

The electric motor 91 for the feeder 87 is controlled by a switch 92 which is biased toward closed position by means of a spring 93 and which may be opened by a solenoid 94 controlled by a circuit 96. One wire of the circuit 96 leads to a contact member 97 which is disposed to engage the top of the charge on the drum and the other wire leads to a contact 98 disposed to make sliding contact with the side of the ring 21 or 22. Thus when the charge on the drum fills up to such an extent that the contact 97 engages in the charge, the circuit 96 is closed, the solenoid 94 is energized and the switch 92 is opened to stop the motor 91, and thus stops the operation of the feeder 87 to supply charge to the drum. When the charge on the drum falls below the contact 97, the circuit 96 is then opened, the solenoid 94 is deenergized and the switch 92 is closed by the spring 93 to energize the motor 91.

In order to maintain an even rate of combustion of the fuel in the charge and particularly to control the rate of combustion during the initial portion of the travel of the charge on the drum 14, I provide a baffle 101 within the suction chamber which is pivoted at its upper end, as shown at 102. The lower free end of the baffle is disposed to move toward the wall 54 by gravity. Connected to the lower end of the baffle 101 on the opposite side from the wall 54, is a cable 103 leading to a drum 104, driven by a motor 106 through a suitable gear reduction 107. As shown in the drawing, the motor 106 is a reversing motor and is controlled by means of a reversing switch 108

in a manner which will be readily understood from the drawing. Located within the suction chamber between the wall 53 and the baffle 101 is a capsule 109 containing a fluid expansibly responsive to a rise of temperature within the suction chamber. A tube 111 leads from the capsule 109 to a pressure responsive device, such as expansible bellows 112, connected by means of a rod 113 to the switch 108. Should the temperature within the suction chamber become too high, pressure within the capsule 109 will operate the bellows 112 to close the switch 108 and operate the motor 106 in a direction to swing the baffle 101 with its lower end toward the side wall 53 of the suction chamber, thereby restricting the downward flow of air through the charge during the initial portion of the travel of the charge on the drum. Should the temperature within the suction chamber, between the baffle 101 and the wall 53, fall below a predetermined minimum, the fluid within the capsule 109 contracts, causing the bellows 112 to contract and operate the switch 108 to close and cause the motor to run in the opposite direction, whereupon gravity will cause the baffle 101 to move toward the sidewall 54 and thus provide for a larger volume of air to flow through the charge. It is contemplated by my invention that the major portion of the fuel in the charge will be burned between the point where it is charged on the drum and the upper edge of the baffle 101, where it is pivoted at 102. If the charge contains a minimum of moisture, the fuel in it might burn too fast and overheat the grate 19. If the charge contains an excess of moisture, the fuel in the charge would not burn fast enough to bring about the desired sintering. By controlling the rate of air for combustion through the charge in its travel between the point of feed and the upper edge of the baffle 101, I am enabled to control the rate of sintering and provide for a uniform, properly sintered, product. It is also contemplated by my invention, that the motor 106 shall be so geared down as to operate the baffle 101 quite slowly and that the temperature response within the suction chamber between the wall 53 and the baffle 101 will be such that the motor 106 will be stopped by opening of the switch 108 before undesired overtravel is reached in either direction. It will be obvious, however, that limit switches 50 may be employed if desired.

After the charge has passed beyond the upper edge of the side wall 54 of the suction chamber and is on its downward movement on the drum 14, it is engaged by a scraper 114 and is removed from the drum.

From the foregoing, it will be apparent that I have devised an improved sintering furnace which is continuous and automatic in its operation, is of large capacity, and is one in which the combustion is so controlled that there is no danger of the parts becoming overheated. It will further be seen that I have devised an improved means to control both the rate of feed and the rate of combustion in the furnace.

While I have shown my invention in but one form, it will be obvious to those skilled in the art that it is not so limited, but is susceptible of various changes and modifications, without departing from the spirit thereof, and I desire therefore, that only such limitations shall be placed thereupon as are specifically set forth in the appended claims.

What I claim is:

1. A sintering furnace comprising a hollow rotary drum having a gas permeable surface,

means defining a stationary suction chamber within the drum, said chamber having an open top subtending an arc within the upper quadrant of the drum, means to feed a sintering charge of ore and fuel onto the surface of the drum to be carried thereby over the suction chamber, means to ignite the fuel in the charge at the beginning of its travel on the drum, suction means connected to the bottom of both ends of the suction chamber to draw air for combustion through the charge, a movable baffle extending longitudinally within the suction chamber intermediate its sides for varying the suction through the charge during the initial portion of its travel, a motor operatively connected to the baffle for varying its position, and temperature responsive means within the chamber for controlling the motor.

2. A sintering furnace comprising a rotary drum having a gas permeable surface for supporting a sintering charge, a stationary suction chamber mounted within the drum and having an open top subtending an arc in the upper quadrant of the drum and having side and end walls cooperating with the surface and ends of the drum to seal off the remainder of the surface of the drum, suction conduits connected to the bottom of both ends of the suction chamber, a baffle extending longitudinally within the chamber in-

termidate the sides thereof and suspended from its upper edge therein, a motor operatively connected to the lower portion of the baffle to vary its position in the chamber, and means responsive to temperature within the chamber for controlling the motor.
